OIL BURNING FURNACE

Bertrand P. Thornton, Lawrence, Kans., assignor,
by direct and mesne assignments, to General
Heating Equipment Company, Kansas City,
Mo., a common-law trust

Application March 31, 1937, Serial No. 134,075
Renewed November 28, 1938

7 Claims. (Cl. 158—53)

My invention relates to oil burning furnaces, and more particularly to an oil burning furnace that is provided with oil burning means that forms a gas, or vapor, of the oil and mixes this with air to produce a combustible gaseous mixture.

It is a purpose of my invention to provide an oil burning apparatus of high efficiency that is adapted for the burning of a heavy grade of oil, and which makes maximum use of the fuel value in the heavy oil that is utilized therein. In order to accomplish this purpose, oil and air are fed to a rotatable member from above the same to the upper surface thereof, said rotatable member comprising part of the oil burning apparatus and serving to thoroughly mix the air and oil and turn the oil into a gasified condition, so that an intimate mixture of air and gasified oil will take place within said rotatable means to cause a highly combustible mixture to be discharged therefrom at the periphery thereof where the combustion takes place.

More particularly my apparatus comprises a rotatable member having blades on the upper face thereof, and means for supplying air and oil to the top side of said rotatable member substantially at the axis of rotation thereof, said blades being so shaped as to create a whirl of said oil and air to thoroughly mix the same, the oil during such mixing being heated by the rotatable member to turn the same into a gas.

It is an important purpose of my invention to provide an apparatus of the above mentioned character, that is provided with means on the axial center thereof for diverting the oil supplied to the same and the air in an outward direction toward the periphery of said rotatable member, and to provide a rotatable mounting for said rotatable member, located entirely below the combustion chamber of my improved oil burning furnace.

The rotation of the rotatable member is, preferably, obtained by means of the air entering through the air supply means, the amount of air supplied being automatically directly proportioned to the amount of oil supplied, inasmuch as the greater the heat within the combustion chamber the more rapidly the air will be supplied through the draft means to the rotatable member, thus rotating the same at a more rapid rate. However, if desired, and particularly for starting purposes additional means may be provided to supply a draft of air to the rotatable member to cause initial rotation thereof, par-

ticularly when the burner is cold at the beginning of the operation of the furnace.

It is an important purpose of my invention to provide, in an oil burning furnace of the above mentioned character, means for transferring a maximum amount of heat from the combustion of the fuel to air that is utilized for heating a room, or other space, or spaces, said means comprising tubular members extending at an inclination to the vertical in an annular series, and forming a plurality of connecting passages between a fire box and combustion chamber.

Other objects and advantages of my invention will appear as the description of the drawings proceeds. I desire to have it understood however, that I do not intend to limit myself to the particular details shown or described, except as defined in the claims.

In the drawings:

Fig. 1 is a vertical sectional view through my improved oil burning furnace, certain parts being shown partly in elevation.

Fig. 2 is a fragmentary vertical sectional view through said furnace, on a somewhat enlarged scale, showing the oil burning apparatus in section.

Fig. 3 is a section taken substantially on the line 3—3 of Fig. 1.

Fig. 4 is a fragmentary top plan view of the oil burner.

Fig. 5 is a fragmentary view, partly in top plan and partly in section, taken substantially on the line 5—5 of Fig. 1, and

Fig. 6 is a fragmentary view in vertical section, of a modified form of oil burning apparatus as applied to an ordinary furnace fire box, or fire pot.

Referring in detail to the drawings, in Figs. 1 to 5, inclusive, is shown the preferred form of my invention, in which the oil burning apparatus comprises a housing having a vertical side wall 10, which is, preferably, cylindrical and provided with the legs 11 at the lower end thereof for mounting the apparatus on any suitable support 12. A transverse wall 13 is provided that is spaced upwardly from the bottom edge of the cylindrical side wall portion 10 and is, preferably, integrally united therewith in any suitable manner, as by welding. A concavo-convex downwardly curved top wall 14 is provided, extending from the top edge of the cylindrical wall 10 and integrally united therewith. A downwardly depending wall portion 15 is provided at the center of the top wall, which is provided with a transverse bottom wall 16 having a central opening 17, in which the 55

air supply conduit 18 is, preferably, welded so as to provide a gas-tight joint between the conduit 18 and the downward extension 15 at the opening in the transverse wall 16. The downward extension 15 of the top wall 14 is provided in order to obtain additional heating surface and to direct the flame and products of combustion in the proper direction.

A lower body portion for the heating apparatus 10 is thus provided, that comprises an upper fire box portion 19 and a lower skirting portion that provide an air chamber 20 that is open to the air space 21 within the outer casing, or housing, 22 of the hot air furnace. The transverse wall, or partition, 13, separating the chamber 20 from the fire box portion 19 has mounted thereon a concavo-convex base plate 23, which has its highest point located at the center thereof and is provided with a peripheral lip, or upstanding rim portion, 24, the 15 lowest point on the upper surface of said base plate 23 being adjacent the flange 24, and a drain pipe 25 extending therefrom downwardly through the air space 20 and outwardly through the outer casing 22 of the furnace. Suitable refractory 20 material, such as fire clay, 26, is placed between the flange 24 and the side wall 10 of the fire box, the refractory material, or ring, having the top surface 27 thereof sloping downwardly toward the flange 24, so that if any oil accumulates thereon it will flow toward the flange 24 and eventually to the drain 25.

My improved heating apparatus further comprises an upper drum, or chamber, 28, which is provided with a substantially cylindrical vertical side wall portion 29, a substantially flat bottom 30, and a concavo-convex top wall 31 that is of a dome-like character and is provided with a central flanged opening 32 that leads to a flue pipe 33. An annular series of openings 34 is provided in the 40 top wall 14 of the fire box, and a similar annular series of openings 35 is provided in the bottom wall 30 of the upper drum-like combustion chamber 28. Tubular members 36 are mounted in the openings 34 and 35 and extend between said fire box 19 and combustion chamber 28, providing 45 communication between the same. In assembling the device, the tubular members are inserted in the openings 34 and 35 and the upper drum-like member 28 is turned, about the vertical axis 50 thereof, relative to the lower main body portion of the oil burning apparatus, as far as possible, so as to throw the tubular members 36 out of vertical position into an inclined position, so that the same lie substantially on the surfaces of 55 spirals after this has been done. After this twist of the upper member relative to the lower member, with the pipes in position, has taken place, the tubular members 36 are fixed in position in the openings 34 and 35 in any suitable manner, 60 as by welding, so as to provide for their retention in the angular position referred to, and to provide gas-tight joints between said tubular members and walls of the fire box 19 and combustion chamber 28.

The transverse bottom wall 13 of the fire box is provided with a substantially centrally located opening, in which is mounted a bearing 37 for a vertical shaft 38, said bearing 37 being secured in the member 13 in any desired manner, as by 65 means of threads 39. An annular inwardly extending rib 40 is provided on the bearing member 37, with which the shaft 38 contacts. The lower end of the shaft 38 is, preferably, beveled off to a point, as indicated at 41, and seats in a 70 conical bearing 42, provided in the bearing mem-

ber 43, which is mounted on a plate-like member 44 secured in spaced position below the partition 13 by means of the bolts, or other securing members, 45. Means is provided for lubricating this bearing, comprising the lubricating oil supply 5 pipe 46, extending outwardly through the wall 10 to a point externally of the furnace where an oil cup 47 may be provided, so that the bearing may be periodically lubricated. Secured in fixed position on the upper end of the shaft 38 is a rotor 10 having a hub portion 48, which is shown as being connected with the shaft by a screw-threaded connection 49, although any other suitable means for fixing the hub member 48 on the shaft 38 to rotate therewith, may be provided. Said hub 15 portion extends through a central opening 50 in the concavo-convex base plate 23, as will be evident from Figs. 1 and 2. The upper end of the hub member 48 is beveled off to provide a conical wall portion 51 thereon, extending from the 20 central peak, or high point, 52 on said upper surface of said hub member downwardly toward the side portion of said hub.

The rotor further comprises a bottom wall 53 that is of a concavo-convex character conforming substantially to the shape of the base plate 23 and lies closely adjacent thereto so as to have just sufficient clearance therefrom for free rotation of the rotor. Integrally united with the hub portion 48 and extending upwardly therefrom, and also 30 integrally united with the bottom wall 53 of said rotor, are the mixing and propeller blades 54. The shape of said blades is shown in Fig. 5, the same curving from the hub portion 48 to the peripheral edge 55 of the bottom wall 53 of the rotor, said 35 rotor being circular, as is obvious from the drawings, so that a stream of air passing downwardly upon the rotor will engage with the concave sides 56 of said curved blades 54 and cause rotation of said rotor in the direction of the arrow on Fig. 5. 40 The bottom edges of the blades 54 conform to the shape of the top face of the bottom wall 53 on said rotor, while the top edges 57 thereof are substantially straight except for the beveled, or inclined, portions 58 extending downwardly to the 45 outer edge of the conical top face of the hub 48.

Mounted on the blades 54 is a top plate, or top closure member, 59, having a central opening 60 of a diameter such that the edge of the opening is co-incident with the point at which the downwardly beveled top edges 58 of the blades 54 begin. Said top plate 59 is secured in position in the rotor by means of pairs of ears 61 punched out of the top plate and bent down into close engagement with the opposite faces of the blades 55 65. If desired, upwardly extending blades, or ears, 62 may also be provided on said top plate 59 for a purpose to be later described.

The air supply conduit 18 extends from externally of the outer casing 22 of the furnace inwardly to above the fire box 19 in spaced relation thereto, and is provided with a sweeping curve 63 therein, so that said conduit extends vertically from a point above the downward extension 15 of the top wall 14 through said extension and 65 through the bottom wall 16 thereof terminating close to the top plate 59, the end 64 of said conduit 18 having just sufficient clearance from the top plate 59 so that there will be no possibility of accidental engagement of the parts to interfere with the rotation of the rotor. It will be noted that the passage in the member 18 is substantially the same size as the opening 60 so that substantially all the air passing through the conduit 18 will pass through the opening 60 into 70 75

the rotor. As the air passes into the rotor, it is deflected outwardly and downwardly by the conical top face 51 of the hub 48 into the portion of the rotor provided with the blades 54, engaging said blades to cause rotation of said rotor, and is thrown outwardly toward the outer edge of the annular rotor member at the periphery of the same.

Oil is supplied through the oil conduit, or pipe, 10 65, the outlet end 66 of which is just a little above the end 64 of the air conduit 18, said oil conduit 65 being located centrally of the air conduit 18 so that the oil is supplied to substantially the center 52 of the conical top wall 51 of the hub 48, and thus spread out and evenly distributed by said conical end wall of the hub between the propeller blades 54, as it is caught in the whirl of air created by said blades 54. As the oil conduit 65 and the air conduit 63 both extend through the combustion chamber and air heating space of the furnace, the air and oil will be heated to such a temperature that when the oil passes into the rotor, or bladed member, it is turned into a gas and thoroughly mixed with the air, which has been heated to a point close to the combustion temperature. Thus no material lowering of the temperature of the flame is caused by the entrance of cold air, and cold oil, into the same, as would otherwise be the case. The supply of oil 20 is controlled by any suitable valve 67 and the proper mixture of air and oil is automatically controlled by means of the setting of the valve 67, inasmuch as the greater the heat created in the fire box, the greater the draft through the pipes 30 36 and the flue pipe 33, and the greater the entrance of air through the draft supply, or air supply, conduit 18. This causes the rotation of the rotor to be in proportion to the draft created, and also thus in proportion to the oil supplied, 35 40 the speed of rotation of the rotor and the amount of air supplied being substantially directly proportional to the quantity of oil supplied to the oil burning apparatus.

In order to prevent any flow of oil to the oil 45 burning apparatus accidentally when the same is not in operation, or in case the same is not operating properly to consume the oil, the safety valve 68 is provided in the oil line 65, which is closed by the oil receiving member 69 that is of a bucket-like form, and receives the oil from the 50 overflow conduit 25, a suitable rod-like member 70 connecting the valve 68 with said bucket 69 to close the valve 68 and prevent flow of oil to the oil burning apparatus, when a predetermined 55 weight of oil collects in said bucket.

Under certain circumstances, it may be desirable to provide additional means for propelling the rotor, although this is ordinarily not necessary. Such means may, however, be desirable 60 when the burner is first started, so as to obtain a thorough mixture of the oil and air by means of the propelling and mixing blades 54 before the heat in the fire box has reached such a point that the natural draft through the air supply pipe 18 65 will be sufficient to rotate said rotor at the desired speed. Such means may comprise an air supply conduit 71, extending through an opening in the side wall 10, within which the tubular member 71 is secured in fluid-tight relation, said 70 tubular member being flattened at 72 to provide a reduced nozzle-like opening 73 in the end thereof to supply a blast of air to the ears 62 on the top, or cover member, 59 to rotate said rotor. Preferably, artificial draft means for the air supply pipe 71 is provided, comprising any suitable 75

fan 74, driven by any suitable means, such as the motor 75, mounted in any suitable manner, as by means of a bracket 76 on the outer wall, 22, of the furnace.

While the oil burning apparatus described above is preferred, and the highest efficiency thereof is obtained by utilizing the fire box and combustion chamber with the inclined tubes 36 connecting the same, as described above, my improved oil burning apparatus may also be utilized in an ordinary hot air furnace, such an arrangement being shown in Fig. 6, the only change in the structure from that shown in Figs. 1 to 5, inclusive, being that a plurality of upstanding post-like members 77 are provided on the base plate 1 23 that support a plate 84, that is provided with a pair of annular ribs 85 and 86, on the upper face thereof, said plate-like member being secured in fixed position by any suitable means, such as the nuts 78 and 79, engaging suitable threaded portions on the members 77.

Refractory blocks, or plate-like members, 80 are provided, which have their lower ends mounted between the ribs 85 and 86 and which are arranged in an outwardly and upwardly inclined 2 position, the upper reduced ends 81 thereof engaging the side wall 82 of the ordinary fire box, or fire pot, of the ordinary hot air furnace, said upper ends being reduced, to provide spaces 83 between the same, through which the flame and 3 products of combustion will pass to the upper part of the fire box, said refractory members throwing the flame outwardly toward the walls of the fire box in a manner similar to that commonly used in ring gas burners in hot air furnaces. 31

Of course, in the ordinary hot air furnace, suitable supporting means must be provided for the plate-like member 13, such as that shown, and the air conduit 71 must be inserted through the fire door opening 90. A similar door opening is 41 provided in my improved type furnace in order to obtain access to the oil burner mechanism, said opening being indicated by the numeral 91 and comprising a box-like housing 92 that leads to the door 93, provided in the outer casing 22 of 45 the furnace, the rectangular housing 92 forming, of course, an air-tight wall between the outer casing 22 and the vertical wall 10, defining the passage 91. A suitable cold air inlet 96 is, of course, provided, as in the ordinary hot air furnace, and 50 hot air conduits are connected with the annular flanges 95, surrounding the openings 94 provided in the top wall of the furnace.

What I claim is:

1. An oil burning apparatus of the character 55 described, comprising a rotatably mounted member having an annular body portion, curved blades on the upper surface of said annular body portion, a cover over said blades having a central opening, an air conduit extending downwardly 60 into proximity to said opening and discharging air into the same, an oil supply pipe in said air conduit extending into proximity to said central opening, and deflector means mounted centrally of said annular body portion directing said oil 65 and air outwardly toward said blades.

2. An oil burning apparatus of the character described, comprising a rotatably mounted member and means for rotating the same, said rotatably mounted member having an annular body 70 portion having an upper surface sloping downwardly from the center thereof toward the rim thereof, blades on the upper surface of said annular body portion, a cover over said blades spaced from said upper surface and having a 75

central opening, an air conduit extending downwardly into proximity to said opening and discharging air into the same, and an oil supply pipe in said air conduit extending into proximity to said central opening and discharging oil into the same.

3. An oil burning apparatus of the character described, comprising a base plate sloping downwardly from the center toward the periphery thereof, a rotatably mounted member mounted over said base plate and having an annular body portion, curved blades on the upper surface of said annular body portion, a cover over said blades having a central opening, an air conduit extending downwardly into proximity to said opening and discharging air into the same, and an oil supply pipe in said air conduit extending into proximity to said central opening.

4. An oil burning apparatus of the character described, comprising a base plate sloping downwardly from the center toward the periphery thereof, a rotatably mounted member mounted over said base plate and having an annular body portion having an upper surface sloping downwardly from the center thereof toward the rim thereof, curved blades on the upper surface of said annular body portion, a cover over said blades having a central opening, an air conduit extending downwardly into proximity to said opening and discharging air into the same, and an oil supply pipe in said air conduit extending into proximity to said central opening.

5. An oil burning apparatus of the character described, comprising a base plate sloping downwardly from the center toward the periphery thereof, a rotatably mounted member of smaller diameter than said base plate mounted closely adjacent the upper face of said base plate, said rotatably mounted member having an annular body portion having an upper surface sloping downwardly from the center toward the rim

thereof and conforming substantially to the shape of said base plate, curved blades on the upper surface of said annular body portion, a cover over said blades having a central opening, an air conduit extending downwardly into proximity to said opening and discharging air into the same, an oil supply pipe in said air conduit extending into proximity to said central opening, and means for draining oil from said base plate adjacent the periphery thereof.

6. In an oil burning apparatus of the character described, a fire box, a vaporizing member mounted in said fire box to rotate on a substantially vertical axis, said fire box having a closed bottom, an air supply conduit of less diameter than said vaporizing member extending into said fire box and having a substantially vertically extending portion terminating in a discharge outlet located above and near the center of the upper surface of said vaporizing member, oil feeding means extending downwardly in said air supply conduit and having the discharge end thereof located within said conduit adjacent its lower end to feed oil to said upper surface, and means for rotating said vaporizing member.

7. An oil burning apparatus of the character described, comprising a vaporizing member mounted to rotate on a substantially vertical axis, a pipe feeding oil downwardly centrally onto the upper surface of said vaporizing member, an air supply conduit extending downwardly toward the center of the upper surface of said vaporizing member and bladed means on said vaporizing member for rotating the same, said bladed means projecting from the upper surface of said vaporizing member and being shaped to mix the oil vaporized by said vaporizing member with said air and direct the combustible mixture so produced to the rim of said vaporizing member upon rotation thereof.

BERTRAND P. THORNTON.
